UNITED STATES PATENT OFFICE.

EDWARD W. CLARK, OF LOS ANGELES, CALIFORNIA, ASSIGNOR OF ONE-HALF TO
STANLEY S. TURNER, OF PASADENA, CALIFORNIA.

CORE-BOX.

1,247,981.

Specification of Letters Patent. Patented July 20, 1920.

Application filed June 30, 1919. Serial No. 309,230.

To all whom it may concern:

Be it known that I, EDWARD W. CLARK, a citizen of the United States, residing at Los Angeles, in the county of Los Angeles and State of California, have invented new and useful Improvements in Core-Boxes, of which the following is a specification.

My present invention relates to core boxes for making the cores for pistons for internal combustion engines and the like and is of a character such as is shown and described in my application for patent, filed October 31, 1918, Serial Number 261,426.

In my said previous application for patent, I have shown a form of core box having a plurality of blades adjustable longitudinally of the axis of the cylindrical body for forming rib recesses in the periphery of the core, in order that corresponding ribs may be provided on the finished piston in the casting operation for reinforcing the piston walls and head and thus providing a piston of minimum weight. The main object of my present invention is to provide in a core box of the character referred to a plurality of ribs or blades adapted to be adjusted radially in the walls of the core box body with respect to the axis thereof, for the purpose described.

A further object of my invention is to provide means whereby all of the said blades may be simultaneously moved into and from operating position by common means and for locking said blades in selected positions. Other objects may appear as the description progresses.

Referring to the drawing, forming a part of this application and annexed hereto, I have shown one practical embodiment of my invention, the details and arrangement of the parts of which will be hereinafter referred to and indicated by means of like reference characters for like parts.

Figure 1 is a plan of my core box; Fig. 2 is a sectional elevation on line 2—2 of Fig. 5;

Fig. 3 is a section on line 3—3 of Fig. 5;

Fig. 4 is an exterior elevation partly in section;

Fig. 5 is a sectional plan on line 5—5 of Fig. 2;

Fig. 6 is a fragmentary view of one of the blade adjusting rings;

Fig. 7 is a perspective view of one of the rib recess forming blades.

It will be understood that while I have shown herein one means of accomplishing the objects of my invention, other means may be employed for this purpose with equally good results, my present invention being only to illustrate and describe a suitable method and the use of the elements which coöperate to produce the desired results.

A convenient form of core box for the purposes of this invention comprises halved separable body members B having semi-cylindrical portions 1, 1, and conical portions 2, 2, so formed that when the two like body portions are placed together the portions 1, 1, will form a perfect cylinder and the portions 2, 2, will form a perfect cone, as shown.

A head forming member H, is provided for molding the end of the core and this member forms a base upon which the body members B may be held during the core making operation. Head member H has a central bore or seat 3, adapted to receive the lower end of the body members 1, 1, and in the center thereof, a lug 4 is provided which extends upwardly into the body B and concentrically formed around said lug is an annular rib 5 also extended upwardly into the body, said lug and said rib serving to form corresponding recesses in the end of the piston core.

Body B, has an annular rib 6 formed on the inner periphery of the wall thereof adjacent to the conical portions 2, 2, which forms a corresponding recess in the end of the core, so that a reinforcing rib may be provided on the end of the piston. The conical portion 2 of the body, which is substantially larger than the cylindrical portion thereof, constitutes a core print molding element. At the lower end of the body member the cylindrical wall has a greater thickness, as at 7, than the upper portion, for the purpose of reducing the diameter of the core at the head in order that the piston produced thereby may be increased in thickness at this point for providing ring grooves.

Head member H has a plurality of radially formed grooves 8, 8, etc., provided in the outer annular portion 9 thereof and the wall portion 1 of the body B, has slots 10 formed therein which are adapted to register with said grooves when the core box

elements are in proper operative relation. In opposite points in the wall portion 1 of the body, I provide removable wrist pin boss members 11, 11, which form corresponding recesses in the periphery of the core, by means of which when the piston is cast, the wrist pin bearings are formed on the piston. The wall slots 10 in the radial plane of said pin bosses extend only from the head of the core to the peripheries of the members 11, 11, and blades 12, 12, are slidably positioned in said slots and have flat extensions 13, 13, integral therewith which are slidably held in the grooves 8, 8, of the head H. These blades 12, 12, may be moved so as to extend a suitable distance into the interior of the body B for forming rib recesses of like character in the core, whereby corresponding ribs will be provided in the piston for bracing the head against the pin bosses.

Intermediate the pin bosses 11, 11, I provide a plurality of elongated blades 14, 14, etc., which are movably supported in the wall slots 10 of the body, the slot for these blades extending from the head H to the junction of the conical and cylindrical portions 1 and 2 of the body, as shown. One of the blades 14 is shown in perspective in Fig. 7. A slight elongation 15 is provided at the upper end of each of said blades and a longer extension 16 at the bottom thereof and the extensions 16 are adapted to movably engage the grooves 8, 8, in the head H.

Each of the blades 14 has an inner extension 17 which is adapted to engage the annular rib 5 on the upper surface of the head H and said extensions are slightly inclined toward the walls of the portions of the body, as shown, while the vertical portions of said ribs are slightly inclined also, as shown. Each of the ribs 12 and 14 has upwardly extended lugs or pins 18 on the rear ends of the extensions 13 and 16 which are adapted to engage curved grooves 19, 19, etc., formed in the lower side of an annular ring 20 adapted to be movably held on the upper side of the head H by means of screws 21 extending through elongated slots 22, as shown, or otherwise. The grooves 19 are eccentrically formed relative to the axis of the body B and the axis of each of the grooves will be a common circle concentric with the axis of the body and head. Thus a movement of the ring 20 in one direction will move all of the blades 12 and 14 inwardly of the body B and a reverse movement of the ring will move the blades outwardly, so that an adjustment of the blades may thus be had to a desired extent.

The screws 21 may be tightened for holding the ring and blades in a desired position for use and the blades are so formed, as shown in Fig. 7, that the depth of the rib recesses in the core varies from the head to

the skirt portion of the blades; thus when the piston is cast from the core made in my mold slightly tapering ribs will be provided on the interior thereof for reinforcing the head and walls.

It will be understood, that, as shown, the core box elements are in position for forming a core, the body B being only loosely held on the head H, and after the core is completed the body B is lifted from the head and inverted so that the core print portion 2 will rest on a suitable base, whereupon the members B may be pulled away from the core horizontally, the blades 12 and 14, however, having first been retracted to positions exterior of the body by the operation of the ring 20.

The core is thus first freed of the rib recess forming blades 12 and 14 and subsequently of the body forming elements, so that the contour of the core will ordinarily be prevented. If desirable, each of the blades may be moved independently by any suitable means and other changes may be made from the disclosure herein made of my invention without departing from the spirit thereof or enlarging its scope beyond the appended claims.

What I claim is:

1. A core box having a body molding portion, and a plurality of peripheral recess forming elements movable radially through said body and into and from contact with the core for the purpose described.

2. A core box having a core mold and a plurality of radially disposed blades laterally adjustable relative to the core and retractile through said mold for forming rib recesses in the periphery of the core.

3. A device of the character referred to, comprising a body having a core molding chamber and a surrounding wall therein, and a plurality of radially disposed blades movably held for adjustment relative to said core molding chamber and retractile through said wall.

4. A core box for pistons comprising a body having a core molding recess, and rib recess forming means movably supported relative to said core molding recess and adapted to be moved transversely and through said body for the purpose set forth.

5. A core box for pistons comprising body molding means including an outer wall and relatively adjustable rib recess molding means supported for movement transversely of said body.

6. A core box having body molding means including an outer wall, and a plurality of simultaneously adjustable blades movable in radial planes relative to the axis of the core and through said wall, and means for holding said blades in desired positions for use.

7. A core box having core body molding means, means adjustably supported relative

thereto for molding recesses in the outer periphery of a core, and means for adjusting said rib recess molding means, as set forth.

5 8. In a core box for pistons, a core body molding element, a head molding element, means movable outwardly and engaging said body and head molding elements for forming rib recesses on the periphery of the
10 core, and means carried by said head molding element for operating said rib recess molding elements.

9. In a core box for pistons, a core body and head molding means, a plurality of
15 radially disposed and outwardly retractible blades capable of extension into said body for forming rib recesses on the core, and an operating member supported on said head molding means for moving said blades.

20 10. In a core box for pistons, body and head molding means, a plurality of radially disposed and outwardly retractible elements capable of extension at will into the core molding recess of said body, and means for
25 operating said blades.

11. In a core box for pistons, separable body and head molding elements, a plurality of horizontally movable blades supported thereon and extensible into the molding recess of said body, said blades being outwardly retractible, and means for operating said blades.

30 12. In a core box for pistons, separable body molding elements including an outer

wall, a head molding element having a recess to receive and hold said body molding element in operating position, and means supported on said body and head molding elements and extending through said wall for forming rib recesses in the core.

35 13. In a core box for pistons, body molding means, end molding means forming a support for said body molding means, corresponding slots being provided in the outer wall of said body molding means and
40 grooves in the side of said end molding means, and a plurality of rib recess forming elements supported in said slots and grooves, and means for moving said rib recess forming elements in planes at right angles to the
45 axis of the body molding means.

50 14. In a core box for pistons, separable body and end molding means having corresponding radiating slots and grooves formed in the outer wall thereof, a plurality of
55 molding elements supported in said slots and grooves and adapted to be moved in planes at right angles to the axis of said body molding means, and means for simultaneously operating all of said movable elements.

Signed at Los Angeles, Los Angeles county,
State of California, this 16th day of June,
1919.

EDWARD W. CLARK.
